(57) **CLAIM**

The new and ornamental design for an electric motor, as shown and described.

DESCRIPTION

FIG. 1 is a perspective top view of the electric motor showing our new design;

FIG. 2 is a top view thereof;

FIG. 3 is a bottom view thereof;

FIG. 4 is a front view thereof;

FIG. 5 is a rear view thereof;

FIG. 6 is a left view thereof; and,

FIG. 7 is a right view thereof.

The broken lines show unclaimed subject matter and form no part of the claimed subject matter.
